UNITED STATES PATENT OFFICE

2,530,560

SAFETY LOCK FOR FIREARMS

Charles A. Young, Gloucester, Mass.

Application July 5, 1947, Serial No. 759,078

4 Claims. (Cl. 42—70)

1

My invention relates to safety devices and, more particularly, to a safety lock for the firing chamber of a rifle, pistol or comparable firearm.

Every year many persons are killed or wounded as the result of accidents with small firearms. In many instances the accidents follow from improper handling of firearms by children or other persons not authorized to operate the guns.

The most important object of my invention is to provide a safety lock for the firing chamber of a firearm in order to prevent the use thereof by unauthorized persons or by persons not in possession of a special instrument necessary for the removal of the lock.

One feature of my invention resides in a tubular sleeve dimensioned to fit within the breach or firing chamber of a gun and provided at its forward end with relatively flexible segments capable of being expanded into locking engagement with the wall of the firing chamber by means of an axially movable plug contained within the sleeve, there being provided a special instrument comprising two wrenches, one of which is adapted to prevent rotation of the sleeve while the other moves the plug axially within the sleeve to expand or contract the relatively flexible inner segments.

I am aware that tompons have been used which embody wedges for locking them into the muzzle of a firearm, but it must be pointed out that such devices merely serve to protect the barrel and do not serve as safety devices. In fact, if the gun were fired with a tompon locked in place, a very serious accident would be inevitable. The purpose of my invention is to prevent the introduction of a shell into firing position in the gun. The lock of my invention may be applied to the firing chamber of a rifle, shotgun, revolver, and similar weapons. In the case of a revolver a separate lock would be provided for each one of the firing chambers. For the sake of simplicity I shall describe an embodiment of my invention, the best embodiment thereof now known to me, as applied to the firing chamber of a rifle. It should be emphasized, however, that the embodiment shown is but one of many and has been chosen for illustrative purposes in the accompanying drawings:

Fig. 1 is a view in cross section through the firing chamber of a rifle showing the lock of my invention in locked position,

Fig. 2 is a view in cross section along the line 2—2 of Fig. 1,

Fig. 3 is a view in cross section through the lock in locked position in a firing chamber,

2

Fig. 4 is a view in cross section along the line 4—4 of Fig. 3.

Fig. 5 is a view from the rear of the breach showing the wrenches in operating position.

5 Fig. 6 is a view in longitudinal cross section of the lock in the firing chamber in unlocked condition with the wrenches in place,

Fig. 7 is a view in side elevation of the plug,

Fig. 8 is a view of the rear end of the lock,

10 Fig. 9 is a view in side elevation of the sleeve,

Fig. 10 is a view in front elevation of the sleeve, and

Fig. 11 is a view in front elevation of the two wrenches.

15 In the drawing I have shown a rifle barrel 10 enclosing a tapered firing chamber 12, all of conventional design. The lock includes a substantially cylindrical sleeve 14 of brass or comparable relatively resilient metal. The sleeve is provided internally with an axial threaded bore 16, and four slots 18 are cut into the end of the sleeve. The intermediate section of the lock comprises a substantially cylindrical portion 20 of somewhat less diameter than the rear half and contains a 20 forwardly tapering bore. Secured to the front end of the lock is a soft nose 60 of lead or similar material. The portion 20 and the nose 60 are provided with four relatively long slots 22 which divide them into four segments, each of which is relatively flexible.

30 A plug 30 is provided at its rear end with threads which engage in the threads of the bore 16 so that the plug may be moved axially along the sleeve 14 by relative rotation therewith. At its forward end the plug 30 comprises an elongated, rounded projection 32 dimensioned to enter the tapering bore in the front half 20 of the sleeve 14 and it will be seen from an inspection of Figs. 3 and 6 that the plug may be rotated to

35 move it axially to the left so that the end of the portion 32 is withdrawn into a position where it does not touch the walls of the tapered bore in the front half 20 of the lock. This condition is shown in Fig. 6 and it will be seen that the segments are not engaged with the walls of the firing chamber 12. Conversely the plug 30 may be turned clockwise to carry it further into the sleeve 14 so that the end of the projection 32 moves into the tapered bore, bears against the walls of the segments 20, and flexes them outwardly until they are firmly engaged with the wall of the firing chamber 12. This condition is shown in Fig. 3. In order to operate the lock, I provide

40 a key comprising a cylindrical member 40 having an integrally formed handle 42 and carrying

45

50

55

on its forward end four lugs 44 dimensioned to fit into the slots 18 in the rear end of the sleeve 14. The rear end of the member 40 is provided with a relatively large bore for the reception of a cylindrical piece 46 having an integral handle 52 and held in the member 40 by means of a snap ring 48 which cooperates with appropriately formed grooves cut into the bore of the member 40 and into the cylindrical piece 46. Fed into the piece 46 and passing through a bore in the member 40 is a hexagonal rod 50. The end of the rod 50 is adapted to enter a hexagonal socket 31 formed in the rear end of the plug 30.

After the lock has been inserted in the firing chamber 12 and tightened in place, the nose 60 effectively prevents it from being driven out rearwardly, inasmuch as the soft lead of the nose 60 will flow around the forward end 32 of the plug 30 and against the wall of the firing chamber 12. The harder the nose is struck, the more will it become deformed and tightened in place.

In inserting the lock into the firing chamber 12 the following procedure is followed: assuming that the plug 30 is in its withdrawn position so that the segments 20 are not stressed, the sleeve containing the plug is pushed into the firing chamber 12 and the key then applied so that the lugs 44 engage the slots 18 in the sleeve 14 and the hexagonal rod 50 is engaged in the socket 31. The operator then holds the handle 42 so that the sleeve 14 cannot turn. Finally the handle 52 is rotated to drive the plug 30 forwardly in the bore 16 until the projection 32 has so far entered the tapered bore that the segments 20 are flexed outwardly into firm locking engagement with the wall of the firing chamber 12. Then the wrenches are removed. It is then impossible to remove the lock from the firing chamber without resorting to the special wrenches. If a screwdriver be inserted to engage a pair of the slots 18, the entire lock will rotate within the firing chamber, provided sufficient torque is exerted. However, this will not effect withdrawal of the lock from the firing chamber. It might be thought that the lock could be removed effectively merely by using a hexagonal spanner to turn the plug 30 and release the segments 20. However, I have satisfied myself by experiments many times repeated that this is not the case. The entire lock will turn. In other words, there is no way to remove the lock except by holding the sleeve against rotation and simultaneously turning the plug in counterclockwise direction. It may be that the plug 30 will turn relative to the sleeve 14 at first, but a point is quickly reached where the whole lock will turn without becoming loose enough to respond to any axial thrust which may be placed upon it. The nose 60, as previously outlined, effectively prevents anyone from driving the lock out by thrusting against it down the barrel.

The wrenches may be relatively quite small and easy to put away in a secreted position or a locked receptacle so that unauthorized persons are effectively prevented from unlocking the gun. The owner of a gun may profitably employ the lock of my invention when on hunting trips, since the gun may be left unguarded and the wrenches conveniently carried in his pocket.

Having thus disclosed my invention, what I claim as new and desire to secure by Letters Patent of the United States is:

1. Safety lock for fireman comprising a sleeve, a plug threaded in the sleeve, a plurality of relatively flexible segments formed in one end of the sleeve and so shaped that the plug may be axially translated to exert a thrust radially against the segments, and soft metal caps secured to the outer ends of said segments.
2. Safety lock for firearms, comprising a substantially cylindrical member having a longitudinal through - and - through bore partially threaded adjacent one end and being adapted at one end to receive a spanner wrench, the opposite end of said member being cut to provide relatively flexible segments, a plug having one threaded portion engaging the threads in said bore and adapted to receive a torque-applying member, and a second unthreaded portion adapted to enter among said segments, the said bore being tapered adjacent to the flexible segments whereby when the unthreaded portion of the plug is forced into that section of the bore, the flexible segments will be forced apart.
3. The safety lock for firearms, comprising a substantially cylindrical member having a longitudinal threaded bore extending from one end thereof to merge with a tapered bore, said cylindrical member being cut to form relatively flexible segments about said tapered bore, the other end of said member being adapted to receive a spanner wrench, a plug threaded into said threaded bore and having a projection adapted to engage the inner surfaces of the segments, the said plug being adapted to receive a torque-applying member for purposes of rotating said plug to move it axially of the said cylindrical member.
4. A safety lock for the firing chamber of a firearm, comprising a sleeve of relatively resilient material, a plug threaded in said sleeve one end of the sleeve and having a tapered bore cut to provide relatively flexible segments, and noses connected one each to said flexible segments, said noses being made of malleable material, the said plug being adapted to receive means for rotating it and the said sleeve being adapted to receive means preventing its rotation.
